CLAIM

The ornamental design for an armoire, as shown and described.

DESCRIPTION

FIG. 1 is a first embodiment of a front perspective view of an armoire in open position showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a perspective view showing the tray in the down position thereof;

FIG. 9 is a front perspective view of the armoire in closed position showing our new design;

FIG. 10 is a front view thereof;

FIG. 11 is a rear view thereof;

FIG. 12 is a left side view thereof;

FIG. 13 is a right side view thereof;

FIG. 14 is a top view thereof; and

FIG. 15 is a bottom view thereof.

FIG. 16 is a front perspective view of a second embodiment of an armoire in open position showing our new design;

FIG. 17 is a front view thereof;

FIG. 18 is a rear view thereof;

FIG. 19 is a left side view thereof;

FIG. 20 is a right side view thereof;

FIG. 21 is a top view thereof; and,

FIG. 22 is a bottom view thereof.

The portions of the armoire shown in broken lines form no part of the claimed design.

1 Claim, 14 Drawing Sheets
